HEEL-SEAT FITTING MACHINE

Filed Sept. 16, 1940

UNITED STATES PATENT OFFICE

2,287,832

HEEL-SEAT FITTING MACHINE

Charles A. Robinson, Salem, Mass., assignor to
 United Shoe Machinery Corporation, Flemington, N. J., a corporation of New Jersey

Application September 16, 1940, Serial No. 356,942

5 Claims. (Cl. 12—31.5)

This invention relates to heel-seat fitting machines and is illustrated as embodied in an improved chip ejector for use in a machine of the general type disclosed in United States Letters Patent No. 1,980,371, granted November 13, 1934, on an application filed in the name of Earl A. Bessom.

In fitting heel seats by the use of a machine such as described in said Letters Patent, the margin of the heel-seat portion of the attached sole of the shoe is forced by a presser member against a crease plate, and the central part of the heel-seat portion of the sole is then forced through a U-shaped opening of the plate and below a flat bottom face of said plate. Heel-breast receiving shoulders are thereafter formed on the sole by a pair of vertically moving knives and the heel-seat portion of said sole is reduced by a knife which travels forwardly with its straight cutting edge in engagement with the bottom face of the plate, said knives removing a horseshoe-shaped chip from the sole to form a heel-seat tab at the rear end of the sole. Preparatory to presenting another shoe to the machine it is necessary to remove the horseshoe-shaped chip, which has been trimmed from the previous sole, from the crease plate and, accordingly, it is common practice to provide an ejector for this purpose.

It is desirable to have the path of movement of the portion of the ejector which contacts the chip spaced slightly from but arranged in close proximity to approximately the entire extent of a beveled sole supporting surface of the crease plate, thereby insuring that chips of different lengths and thicknesses may be effectively removed from the plate. Moreover, it has been found that in operating upon shoes in which rubber cement, for example, has been interposed between the sole and the shoe upper in the vicinity of the heel-breast line, the forward end of the chip frequently sticks to the crease plate, with the result that the rear portion of the chip, especially when thin, has a tendency to rise up over the ejector and, accordingly, is not properly removed from the plate. Furthermore, in order to insure that the ejector shall not be caught under the presser member as the operator raises and lowers the treadle while positioning the shoe in the machine, it is also desirable that the ejector shall not be moved until the shoe has been finally positioned in the machine and power pressing and trimming mechanism of the machine is operated by continued downward move-

ment of the treadle, which continued movement causes a one-revolution clutch to be tripped.

It is an object of the present invention to provide improved mechanism, having the advantages and none of the disadvantages above referred to, for quickly and effectively removing chips from the crease plates of heel-seat fitting machines.

With the above object in view, and in accordance with a feature of the present invention, there is provided a heel-seat fitting machine comprising a crease plate having a surface for supporting the heel-seat portion of the sole of a shoe, means for reducing the heel-seat portion of the sole to form a heel-seat tab, an ejector, and means for moving the ejector over the crease plate to remove from the plate a chip trimmed from the heel-seat portion of the sole, said ejector comprising a bar conforming generally to the transverse curvature of the sole engaging face of the crease plate, the bar having a flange which is constructed and arranged to override the rear end of the chip upon the crease plate in order to insure that the bar shall not slide under the chip, as above described.

The illustrative ejector is pivoted at its upper end upon a fulcrum pin which may be secured in different adjusted positions to the machine frame and is so constructed and arranged that the ejector bar, during its chip ejecting movement, will swing in a path which is located adjacent to and extends along a work supporting face of the crease plate, thereby insuring that the bar shall engage the chip and effectively remove it from the crease plate irrespective of the thickness or the length of the chip. The ejector is normally held in its rearward position against a stop by a spring and is swung forwardly over the crease plate, to remove the chip therefrom, by an actuator carried by and pivoted upon a housing which carries a presser member adapted to force the margin of the heel-seat portion of the sole against the plate. The housing is yieldingly secured to a plunger which is movable vertically toward and away from the crease plate and has secured to its lower end a bulger adapted to force the central part of the heel-seat portion of the sole through the U-shaped opening of the crease plate. In order that the ejector shall not be moved forwardly until the presser member and the bulger have been raised a predetermined distance above the crease plate after the completion of the tab forming operation, a latch is pivoted to the actuator and, until tripped by an abutment, serves

to hold the actuator in its idle position in which vertical movement of the actuator does not cause the ejector to move. The abutment, which may be set in different adjusted positions, is so positioned that it does not release the latch from its idle position until after the work has been finally positioned in the machine and a one-revolution clutch, through which the bulger and the trimming knives are operated, has been tripped. The actuator does not engage the ejector to swing the same forwardly over the crease plate, as above described, until after the presser member and the bulger have been moved substantial distances away from the sole. After the actuator has moved the ejector to the forward end of its stroke, said actuator, in turn, is swung rearwardly to its latched, idle position by the ejector as the same moves back to its rearward position against the stop. With the above arrangement the chip trimmed from the heel-seat portion of the sole is quickly and effectively removed from the crease plate without any danger of catching the ejector beneath the presser member during the initial positioning of the work in the machine.

The various features of the invention will be understood and appreciated from the following detailed description read in connection with the accompanying drawing, in which

Fig. 1 is a perspective view of a heel-seat fitting machine, partly broken away, embodying an improved chip ejector;

Fig. 2 is a detail view of said machine as viewed in the direction indicated by arrows II—II of Fig. 1;

Figs. 3 and 4 are side views, partly broken away and partly in section, of the portion of the machine illustrated in Fig. 1 during two progressive stages in the operation of the same;

Fig. 5 is an illustrative view showing in perspective a chip in the process of being removed from a crease plate of the machine; and

Fig. 6 is a perspective view of the heel end portion of a shoe the heel-seat portion of the sole of which has been reduced by the above machine.

The illustrative ejector 20 is described with reference to removing from a crease plate 22 of a heel-seat fitting machine a horseshoe-shaped chip 24 (Fig. 5) which has been trimmed from the heel-seat portion 26 (Fig. 3) of the attached sole 28 (Figs. 3 and 4) of a shoe 30. The illustrative machine, with the exception of the chip ejector 20 and mechanism for operating the same, is practically identical with the machine disclosed in United States Letters Patent No. 1,980,371, granted November 13, 1934, on an application filed in the name of Earl A. Bessom, which patent may be referred to for a complete understanding of the machine and its operation.

The shoe 30 is presented to the machine bottom up and heel end first, the heel-seat portion 26 of the attached sole overlying the crease plate 22. After the shoe has been positioned in the machine by suitable back and centralizing gages 32, 34, respectively (Fig. 1), the operator depresses a treadle (not shown), causing a rod 36 to be lowered against the action of a spring 37 and through suitable mechanism 38 (Fig. 1) a plunger 40 (Figs. 3 and 4) to be lowered. Movable with but yieldingly mounted upon the plunger 40 is a sleeve 42 having at its lower end a housing 44 constructed and arranged to receive a horseshoe-shaped presser member 46 which,

upon downward movement of the plunger, forces the margin of the heel-seat portion 26 of the sole against a beveled face or surface 48 of the crease plate 22. The rear part of the beveled surface 48 may be described as concave widthwise. Rigidly secured to the plunger 40 is a bulger 50 (Fig. 1) which, after the margin of the heel-seat portion 26 of the sole has been clamped against the crease plate 22 by the yieldable presser member 46, as above described, and when a one-revolution clutch (not shown) has been tripped by further downward movement of the treadle rod 36, moves downwardly to force the central part of the positioned heel-seat portion 26 of the sole through a U-shaped opening 52 of the crease plate 22 and below a flat bottom face 54 of the plate, the bulger coming to a stop when its flat bottom face 56 is in alignment with the flat bottom face 54 of the crease plate. After the heel-seat portion 26 of the sole 28 has been clamped and conformed as above described, shoulder forming knives 58 (Fig. 1) are moved downwardly to form heel-breast receiving shoulders 60 (Fig. 6) upon the sole, and a back knife 62 (Fig. 3) moves forwardly with its straight cutting edge 63 in engagement with the bottom face 54 of the crease plate to reduce the heel-seat portion 26 of the sole and in combination with the knives 58 to form a heel-seat tab 64 on the sole.

In order quickly and effectively to dispose of the horseshoe-shaped chip 24 remaining on the crease plate 22 after the heel-seat fitting operation, there is provided the ejector 20 which comprises a curved bar 66 (Figs. 1 and 5) adjustably secured by a slot-and-screw connection 68 to the end of an elongated lever 70 fulcrumed at its upper end upon a threaded pin 72 carried by the upper end of a bracket 74 mounted upon a large screw 76 threaded into a boss 78 of the machine frame. The bracket 74 may be initially set in its proper operating position about the screw 76 so as to insure that the bar 66 shall swing along the sole engaging face 48 of the crease plate 22, such adjustment being readily effected through the provision of a screw 80 which passes through a slot 82 in the bracket 74 and is threaded into the boss 78. As will appear later, the screw 80 also serves to secure to the bracket 74 a stop 84 which limits rearward movement of the lever 70.

The fulcrum pin 72 is so positioned that the bar, which is conformed generally to the transverse curvature of the face 48 of the crease plate 22, will at all times be in close proximity to the crease plate during its sweeping movement over the crease plate. Accordingly, the chip 24, regardless of its size, will be effectively pushed off the forward end of the crease plate during forward movement of the bar 66. As above stated, there is a tendency for the forward end of the chip 24 to stick to the crease plate 22, with the result that, unless there is some provision for preventing this action, a thin, flimsy chip will sometimes override the bar 66 as the bar swings forwardly. With the foregoing in view, the bar 66 is provided with a flange 86 which is shaped and arranged to override the rear end of the sole and insures that the chip shall not slip over the bar as above described.

Secured by a screw 88 to the upper end of the lever 70 and pivoted upon the fulcrum pin 72 is an abutment lever 90 which has at its forward end an offset flange 92 (Fig. 1) into which is threaded a trip screw 94. The lever 70, together

with the abutment lever 90, forms in effect an integral bellcrank lever 91 and may be referred to as such. The offset flange 92 is provided with a beveled face 96 (Figs. 3 and 4) the lower end of which is at all times in contact with an actuator 98 the construction and operation of which will appear later. When the machine is at rest, the lever 70 is held in engagement with the stop 84 by a coil spring 100 the lower end of which embraces the screw 88 and the upper end of which is fixed to the machine frame.

The ejector 20 is operated by the actuator 98 which is mounted upon a fulcrum pin 102 secured to the housing 44 of the sleeve 42 and is constantly forced against the flange 92 of the abutment lever 90 by a spring 104 the lower end of which engages the housing and the upper end of which embraces the rear face of the actuator. Pivoted upon a fulcrum pin 106 carried by the actuator 98 is a latch 108 which is constantly urged downward by a spring 110, a shoulder 112 of the latch being in approximate engagement with a face 114 of an arrester plate or retainer member 116 carried by the plunger 40, as shown in Fig. 3, when the machine is idle. The initial positioning of the arrester plate 116 upon the plunger may be readily varied through the provision of a screw 118 which is threaded into the plunger and passes through an elongated slot 120 of said plate.

The ejector 20 is swung forwardly against the action of the spring 100 by the engagement of a shoulder 122 (Figs. 2 and 3) of the actuator with the flange 92 of the lever 90, during upward movement of the plunger 40 and after the completion of the trimming operation, the actuator having previously been moved from its inoperative or idle position shown in Fig. 2 to its operative position shown in Figs. 3 and 4. In order to trip the actuator 98 so as to cause the shoulder 112 of the latch 108 to be arranged above the arrester plate 116, there is provided a block 124 which is adjustably secured to the bracket 74 by a screw-and-slot connection 126 and is engaged by the latch 108 during the downward movement of the plunger 40. It is quite important that the latch 108 shall not be released until the clutch (not shown) has been tripped since the operator sometimes raises and lowers the treadle rod 36 several times in positioning the work in the machine, and if said latch were released before tripping the clutch, there would be a tendency for the bar 66 of the ejector to be caught beneath the presser member 46. Accordingly, the block 124 is so adjusted that the latch 108 is released while the bulger 50 is forcing the central part of the heel-seat portion of the sole through the U-shaped opening, such action occurring immediately after the one-revolution clutch of the machine has been tripped.

As the plunger 40 is raised, the shoulder 122 of the actuator 98, which has been moved beneath the flange 92 of the bell-crank lever 91 by the spring 104, engages said flange 92, causing said lever to swing in a counterclockwise direction, thereby sweeping the chip 24 from the crease plate 22 and into a hopper (not shown) of a chip collector. In order to insure that the chip 24 shall not be flipped from the crease plate 22 by the ejector 20, the rate of upward movement of the plunger 40 under the action of spring 37 is reduced through the provision of a fluid check 128.

As the ejector bar 66 reaches the forward end of its stroke, as illustrated in Fig. 4, the trip

75 screw 94, by reason of its engagement with face 130 of the actuator 98, causes the lower edge of the face 96 of the flange 92 to run off the ledge 122 of the actuator, with the result that the ejector is permitted to swing in a clockwise direction back to its starting position, shown in Figs. 1 and 2, under the action of the spring 100, during which time the lower edge of the face 96 of the ejector 20, operating against an inclined face 132 of the actuator 98, moves said actuator in a counterclockwise direction, against the action of the spring 104, back to its latched starting position shown in Fig. 2.

Having described my invention, what I claim as new and desire to secure by Letters Patent of the United States is:

1. A heel-seat fitting machine having, in combination, means constructed and arranged to conform the heel-seat portion of a sole to a predetermined shape, said means comprising a crease plate having a concave work supporting surface, one or more knives for trimming a chip from the conformed heel-seat portion of the sole to form a heel-seat tab on the sole, an ejector having a work engaging portion mounted for swinging movement over and in close proximity to but spaced from said work supporting surface of the crease plate about an axis which is spaced a considerable distance from said plate and extends widthwise of the plate, mechanism for operating the ejector to remove the chip from said crease plate, and means for varying the position of the axis about which the ejector is swung lengthwise of the plate.

2. In a heel-seat fitting machine, a crease plate having a U-shaped opening, a presser member for clamping the margin of the heel-seat portion of a sole against portions of the crease plate adjacent to said opening, a movable bulger for forcing the central part of the heel-seat portion of the clamped sole through the U-shaped opening, said presser member being yieldingly mounted for movement together with the bulger, one or more knives for trimming a chip from the conformed heel-seat portion of the sole to form a heel-seat tab on the sole, an actuator which is mounted for movement with the presser member and is constructed and arranged to operate the ejector to cause the same to remove the chip from the crease plate, a retainer member positively movable with the bulger, a latch connected to the actuator and constructed and arranged to co-operate with said retainer member to hold the actuator in a predetermined idle position in which its movement with the presser member will not effect movement of the ejector, and a fixed stop constructed and arranged to be engaged by the latch to release the same from its idle position at a predetermined time from the retainer member thereby enabling the actuator to move to an operative position in which its movement with the presser member will cause said actuator to move the ejector so as to remove the chip from the crease plate.

3. A heel-seat fitting machine having, in combination, a crease plate, an ejector which is mounted for swinging movement about a fixed pivot and is constructed and arranged to force a chip from said crease plate, an actuator for operating the ejector, a spring for forcing the actuator against the ejector, a latch for holding the actuator in an idle position away from its operative position in which movement of the actuator causes the ejector to be swung along the crease plate to remove the chip from the crease

plate, and means for releasing the latch from its idle position at a predetermined stage in the operation of the machine, to move the actuator to said operative position, said ejector having portions constructed and arranged to move the actuator, after the chip has been removed from the crease plate, from its operative position to its idle position thereby rendering said latch effective to maintain the actuator in said idle position.

4. A heel-seat fitting machine having, in combination, a crease plate, means for reducing the heel-seat portion of a sole of a shoe to form a heel-seat tab, an ejector mounted for movement, a stop, a spring for constantly urging the ejector toward the stop, a movable actuator constructed and arranged to operate the ejector against the action of said spring to remove from the crease plate a chip trimmed from the heel-seat portion of the sole, a latch associated with the actuator, said ejector being constructed and arranged to move the actuator, after the chip has been removed from the machine, to an idle position in which movement of said actuator will not effect movement of the ejector, and to render the latch effective in maintaining the actuator in said idle position, and an abutment for tripping the latch at a predetermined time to

move the actuator to an operative position in which movement of the same will operate the ejector.

5. A heel-seat fitting machine having, in combination, a crease plate, means for reducing the heel-seat portion of a sole of a shoe to form a heel-seat tab, an ejector mounted for swinging movement, a stop, a spring for constantly urging the ejector toward the stop, an actuator mounted for combined translatory and swinging movement, said actuator being constructed and arranged to operate said ejector against the action of said spring to remove from the crease plate a chip trimmed from the heel-seat portion of the sole, a latch pivoted to the actuator, said ejector being constructed and arranged to swing the actuator, after the chip has been removed from the machine, to an idle position in which movement of the actuator will not effect movement of the ejector and to render said latch effective in maintaining the actuator in said idle position, and an abutment for tripping the latch at a predetermined time to move the actuator from said idle position to an operative position in which movement of the actuator will cause the ejector to remove the chip from the crease plate.
